[57] CLAIM

The ornamental design for a retainer clip for pipes, rods and other elongated bodies or the like, as shown and described.

DESCRIPTION

FIG. 1 is a top plan view of a retainer clip for pipes, rods and other elongated bodies or the like showing my new design;

FIG. 2 is a front view thereof;

FIG. 3 is a bottom plan view thereof;

FIG. 4 is a side view taken from the left of FIG. 2;

FIG. 5 is a side view taken from the right of FIG. 2;

FIG. 6 is a sectional view taken in the direction of the arrows on line VI—VI in FIG. 2;

FIG. 7 is a top and left front perspective view thereof;

FIG. 8 is a bottom and right rear perspective view thereof;

FIG. 9 is a front view thereof, the portions of a panel and elongated bodies being shown in broken lines for illustrative purposes only;

FIG. 10 is a top plan view of a second embodiment of the design of FIG. 1;

FIG. 11 is a front view of FIG. 10;

FIG. 12 is a bottom plan view thereof;

FIG. 13 is a side view taken from the left of FIG. 11;

FIG. 14 is a side view taken from the right of FIG. 11;

FIG. 15 is a top and left front perspective view of FIG. 10;

FIG. 16 is a bottom and right rear perspective view of FIG. 10.
